UNITED STATES PATENT OFFICE.

WILLIAM D. WILDER AND FREDERICK W. COWAN, OF BROCKTON, MASSACHUSETTS.

SHOE-TREE.

No. 925,736.

Specification of Letters Patent.

Patented June 22, 1909

Application filed April 27, 1908. Serial No. 429,601.

To all whom it may concern:

Be it known that we, WILLIAM D. WILDER and FREDERICK W. COWAN, citizens of the United States, residing at Brockton, in the county of Plymouth and State of Massachusetts, have invented certain new and useful Improvements in Shoe-Trees; and we do declare the following to be a full, clear, and exact description of the invention, such 10 as will enable others skilled in the art to which it appertains to make and use the same.

This invention relates to shoe trees, and has for its object to provide an improved 15 form of adjustable connections between the fore and heel parts of the tree.

In the annexed drawing forming a part 20 of this specification in which like reference characters refer to like parts throughout the several views and which are for illustrative purposes and therefore not drawn to any particular scale, Figure 1 is a side view of one form of shoe tree; Fig. 2 is a top plan view of the same; Fig. 3 is a longitudinal horizontal sectional view; Fig. 4 is a longitudinal, vertical sectional view, parts being folded; Fig. 5 is a longitudinal, horizontal sectional view of a modification, the parts being extended; and Fig. 6 is a 30 longitudinal, vertical sectional view of a modification, parts being folded.

Referring more particularly to the Figs. 1 and 4 of the drawing, the invention is shown embodied in a shoe tree having a forward portion 1 and a heel portion 2. These 35 members may be made of celluloid or may be made of canvas impregnated with celluloid or other stiffening material which may be spread upon, pressed into or molded upon said canvas.

The forward portion 1 is shaped to conform to the desired contour, the lower edges thereof being turned inwardly and terminated to leave an opening 2 almost the entire 45 area of the sole of the shoe. This permits the access of air through the rear part of the forward part of the holder, thus readily drying out the shoe when the holder is in place.

The lower rear part of the lower edges 50 of the forward part are nearly brought together as at 3 and are connected by a downwardly opening U shaped member 4 having laterally extending ends 5 riveted or otherwise secured to the edge of the fore-part as at 3. Pivots secured in said U shaped

member by means of a pin 6; the rearwardly extending forward bar section 7 provided with a plurality of smaller perforations 8 and a larger perforation 9. Slidably mounted upon said section 7 is the rear section 10 provided with a horizontal slot 7 through which and said perforation 9 is passed a clamping bolt to clamp the parts together. The forward end of said section 10 is provided with a laterally extending projection 12 adapted to engage one of the perforations 8 when the sections 7 and 10 are clamped together. The rear end of the section 10 is provided with an upwardly extending portion 13 and the part 2 is fitted to said section 10 and is adapted to press against said upwardly extending portion.

The modification shown in Figs. 5 and 6 is similar to that shown in Figs. 1 to 4, except that the inner edge 14 of the fore-part is provided with a binding strip of sheet metal 15 and a wooden ball 16 is provided in place of the heel part 2.

If desired, the laterally projecting ends 5 50 may be provided with a forwardly projecting part 17, extending into the fore-part, whereby said fore-part is strengthened.

The shoe-tree is operated as follows:—The 55 part 2 or 16 is moved to its upward limit of movement and the fore-part 1 placed in the shoe, then the part 2 or 16 is moved downwardly into the heel of the shoe, whereby the fore-part is firmly held in place, the distance between the fore-part and the heel-part 20 having been adjusted by means of the adjustment between the parts 7 and 10.

When the tree is not in use, the heel parts 60 can be easily thrust through the opening 2 into the fore part as is apparent from an inspection of Figs. 4 and 6. It is of course understood that we may use any or all of the features described in the herein-described modification in any combination desired.

A shoe tree formed as above described 100 forms a perfectly hygienic shoe tree as the material used therein is not absorbent in its nature and because of the heel construction which allows free access to the air when the tree is in use.

Particular attention is called to the method of adjusting the distance between the fore part and the heel part of the shoe tree. A shoe tree of this kind is of very light weight and is therefore specially adapted 110 for use as drummers' samples as freight and express charges would be low when shipping

in large quantities, and a shoe tree of this kind is particularly advantageous for shipping and packing for travelers and may be made of any color desired.

5 Having thus described our invention, what we claim as new and desire to secure by Letters Patent, is:—

1. In a shoe tree a fore part comprising a piece of stiff material forming the upper 10 part of said fore part, the lower edges being turned inwardly and cut away whereby an opening is left extending across the sole of said fore part the rear ends of said edges being brought almost together, an inverted 15 U shaped member having laterally projecting ends riveted to said edges, a forward bar section pivotally connected between the arms of said U shaped member, said bar being provided with a plurality of perforations, 20 a rear bar section having a lateral projection adapted to engage certain of said perforations, and provided with a longitudinal slot, a clamping bolt adapted to pass through said slot and one of said perforations, a nut on

said bolt and a heel part secured to the rear 25 end of said rear bar section.

2. A shoe tree comprising a fore part and a heel part, a connecting bar formed in sections, one of which is provided with a longitudinal slot, and the other with a series of 30 apertures, a securing bolt and nut arranged in the inner ends of one of said sections and adapted to engage the slot in said other section whereby the fore and heel parts of the tree are adjustably connected together, and 35 lateral projections on the ends of said sections to engage the slots and perforations in the opposing sections whereby said sections of the bar are held in rigid alignment.

In testimony whereof we have hereunto 40 set our hands in presence of two subscribing witnesses.

WILLIAM D. WILDER.
FREDERICK W. COWAN.
